J. CZERNIAK

RAILROAD SWITCH OPERATING DEVICE

Filed Jan. 2, 1924

INVENTOR

Joseph Czernicki
BY
John F. Holadny
ATTORNEY

UNITED STATES PATENT OFFICE.

JOSEPH CZERNIAK, OF KENOSHA, WISCONSIN.

RAILROAD-SWITCH-OPERATING DEVICE.

Application filed January 2, 1924. Serial No. 683,880.

To all whom it may concern:

Be it known that I, JOSEPH CZERNIAK, a citizen of the United States, residing at Kenosha, in the county of Kenosha and 5 State of Wisconsin, have invented certain new and useful Improvements in Railroad-Switch-Operating Devices, of which the following is a specification.

This invention relates to a railroad switch 10 operating device by means of which a switch can be operated by one of the crew of an approaching train or engine, from said train or engine, the invention having for an object the provision of a novel switch operating device of this sort.

For further comprehension of the invention, and of the object and advantages thereof, reference will be had to the following description and accompanying drawing, 20 and to the appended claims in which the various novel features of the invention are more particularly set forth.

Fig. 1 of the drawing is a plan view showing my improved switch operating means 25 applied to a railroad track.

Fig. 2 is a side view thereof.

Fig. 3 is a transverse sectional view taken on the line 3—3 of Fig. 1.

Fig. 4 is an enlarged fragmentary plan view showing the switching device.

Fig. 5 is a detail perspective view of the operating device carried on the train.

In the drawing the reference numerals 10 and 11 indicated a pair of tracks rails, while 35 10' and 11' indicate a pair of rail ends which are adapted to connect to the rails 10 and 11 to enable a train to transfer from one pair of rails to the other and which we may consider as the ends of a siding. Extending 40 along the rail 11, which is on that side of the track from which the siding joins it, are pairs of the horizontal bars 12 which extend along opposite sides of the rail parallel thereto and which are slightly spaced laterally therefrom, and may have their 45 top faces substantially flush with the top face of the rail. These bars 12 are provided with a number of downwardly extending lugs 13 to which attach the approximately 50 horizontal arms of a number of bell crank levers 14 which are fulcrumed on the upper ends of the brackets elements 15 fixed to the base flange of the rail 11. Connected to the 55 vertical arms of these bell crank levers are the thrust bars 18 which are adapted to be moved longitudinally when the bars 12 are

depressed, these thrust bars extending along the rail, one on each side thereof, and having their main lengths just above the ties on which the rail rests. The adjustable rail ends 10' and 11' are connected together by means of a transverse link 20 which engages their base flanges in the usual manner by means of claw elements on its ends.

This link is adapted to be shifted longitudinally of itself, that is transversely of the track, by means of a rock-lever 22 which is fulcrumed between its ends as at 23 to a suitable fixed part such as the base element 24 sunk in the road bed below the level of the 60 rails, this lever having a short finger 22' projecting from the centre thereof through which the link 20 is operated. The opposite ends of the lever 22 are adapted to be engaged directly by the adjacent ends of the thrust bars 18 when a train approaches the switch from one direction. When a train 65 approaches in the opposite direction the lever ends are engaged by hooked fingers 24 formed on one end of other levers 25 which are fulcrumed as at 26 to the base element 24, these levers having their opposite ends 70 projecting across the ends of the thrust bars 18 to be operated by the latter, the end portions of the thrust bars being depressed below the level of the rails as at 18', so as to clear the rail elements 10' and 11. As will be 75 readily understood, when one of the bars 12 is depressed the switch ends will be moved in one direction, and when the other of said bars is depressed the switch ends will be moved in an opposite direction.

The connection between the finger 22' and the link 20 is effected through the medium of a gear sector 30 on said finger which engages a gear pinion 31 fixed to a spindle 32 rotatable in the base element 24 to which spindle 32 is also fixed an eccentric disk 33 engaging in a suitable aperture in the link midway between the ends of the latter. The parts are so proportioned that the disk 33 makes one-half of a revolution when the lever 22 is rocked by means of either of the thrust bars, the disk coming to rest in dead centre position so that the link is locked 90 against movement until the bar on the other side of the rail is moved.

To depress the desired bar a crank shaft 40 may be mounted on the locomotive or on any suitable part of the train, and is formed with pairs of crank elements 41 to which are connected the bars 42 which extend down-

ward to engage the said bars, having rollers 43 on their lower ends which come into contact with the bars. The lower ends of these bars may be guided by suitable parts. Fixed 5 to the shaft 40 is a handle 45 for rocking the shaft.

As will be apparent from the above description, the engineer or other member of the crew of a train approaching the switch 10 and desiring to change the latter can do so by rocking the shaft 40 in the proper direction to depress the right one of the bars 12 and thereby cause the switch ends to be moved.

15 While I have illustrated and described a preferred embodiment of my invention it is to be understood that I do not limit myself to the precise construction herein shown and that various changes and modifications 20 might be made therein without departing from the spirit and scope of the invention as defined in the appended claims.

Having thus described my invention what I claim as new and desire to protect by Letters Patent of the United States is as follows:

1. In a railroad track, a movable switch end, a depressible bar extending along the track, a thrust bar also extending along the 30 track, bell crank levers connecting said first and second bars whereby depression of the first bar moves the second bar longitudinally, a rock lever adapted for operation by

said second bar, and an operative connection between said rock lever and switch end. 35

2. In a railroad track, a movable switch end, a depressible bar extending along the track, a thrust bar also extending along the track, bell crank levers connecting said first and second bars whereby depression of the 40 first bar moves the second bar longitudinally, a rock lever adapted for operation by said second bar, and an operative connection between said rock lever and switch end, said operative connection comprising a gear segment on the rock lever, a pinion engaged by said segment, an eccentric disk fixed to said pinion, and a link with which said disk is engaged. 45

3. In a railroad track, a rail, a pair of movable switch ends, a pair of bars extending along one of the track rails on opposite sides of the latter, a pair of thrust bars, bell crank levers connecting said first and second 55 named bars whereby depression of the former moves the latter longitudinally, a rock lever fulcrumed midway between its ends and adapted to have opposite arms thereof engaged by the respective thrust bars, a link connecting the said rail ends, and an operative connection between said rock lever and said link. 60

In testimony whereof I have affixed my signature.

JOZEPH CZERNIAK.
